UNITED STATES PATENT OFFICE.

DAVID F. VAUGHAN, OF RIVERTON, NEW JERSEY.

ANTICREEPER FOR RAILROAD-RAILS.

1,244,145.

Specification of Letters Patent.

Patented Oct. 23, 1917.

Application filed December 16, 1913. Serial No. 806,963.

To all whom it may concern:

Be it known that I, DAVID F. VAUGHAN, a citizen of the United States, residing at Riverton, in the county of Burlington and State of New Jersey, have invented certain new and useful Improvements in Anticreepers for Railroad-Rails, of which the following is a specification.

My invention relates to anticreepers for railroad rails, and particularly to anticreepers of that type wherein a bar adapted to extend beneath a rail base is employed in conjunction with means on one end of the bar adapted to engage one side of a rail base and adjustable means on the other end of the bar adapted to engage the other side of a rail base and operative to clamp the anticreeper to a rail.

The primary object of my invention is to provide an anticreeper of the above general character, with a novel, simple, efficient and adjustable means on one end of the bar and operative to firmly clamp the anticreeper to a rail; a further object of my invention is to construct the bar in a novel manner so that when said adjustable means is tightened the bar may be sprung from a normal condition and caused to exert pressure against the bottom of the rail and to press the parts at the ends of the bar down upon the top of the rail base and toward each other and against the sides of the rail base, as the bar tends to resume said normal condition; and a further object of my invention is to construct various different parts of the anticreeper in a novel manner to obtain various novel and advantageous results, as will be herein-after described and particularly claimed.

40 In the accompanying drawings, illustrating my invention—

Figure 1, is a side elevation of a portion of a railroad rail, a portion of a cross tie and my improved anticreeper applied to 45 the rail.

Fig. 2, is an elevation of the parts shown in Fig. 1, as seen from a position looking at one end of the rail.

Fig. 3, is a view showing one position of 50 the parts during the application of the anticreeper to the rail.

Fig. 4, is a view of a modification of the anticreeper.

Fig. 5, is a view showing one position of 55 the parts during the application of the modification shown in Fig. 4 to the rail.

Referring to the drawings, 2 designates a portion of a railroad cross tie and 3 a railroad rail of usual construction. The cross tie 2 forms a stationary part of the road bed which supports the rail and over which the rail tends to creep under the well-known conditions.

My improved anticreeper is applied to the base 4 of the rail 3, and, as herein illustrated, is constructed as follows:

Extending transversely beneath the rail 3 is a bar 5 comprising two straight portions 6 and 7, a downwardly-extending, centrally-arranged loop 8 connecting the straight portions 6 and 7, a rail gripping part or hook 9 formed on the outer end of the straight portion 6 and extending over one side of the rail base 4, and an end portion 10 extending upwardly from the outer end of the straight portion 7 adjacent to the other side of the rail base 4. The upwardly-extending end portion 10 is screw-threaded, and screwed thereon is a rail gripping part or nut 11 adapted to engage 80 the top of the adjacent side of the rail base 4. The end portion 10 is inclined upwardly and outwardly with respect to the adjacent side of the rail base 4; and the screw threads on the inner side of the end portion 10 are cut away so as to present to the adjacent side of the rail base a smooth and uninterrupted face 12 on the end portion 10; both for a purpose presently appearing.

90 The bar 5 is preferably formed of spring metal (although this is not essential in all forms of my invention) and the normal condition of the spring metal bar is as shown in Fig. 3. In the position of the parts, shown in Fig. 3, the hook 9 is engaged with one side of the rail base 4, as shown, the top of the straight portion 6 is engaged with the bottom of the rail base 4, the top of the straight portion 7 is spaced from the rail base 4, the inclined inner face 12 of the end portion 10 above the bottom of the face 9 is engaged with one side of the rail base 4, and the bottom of the inclined face 12 is beneath the adjacent side of the rail base. It will, therefore, be readily understood that if now the nut 11 be turned to raise the end portion 10 of the spring bar 5 to bring the parts into the position shown in Fig. 2, the bar 5 will be sprung vertically from its normal condition to bring the straight portion 7 up against the bottom of the rail base 4;

and that the bar 5 will be sprung horizontally from its normal condition, through its loop 8, as the bar is raised and inclined face 12 acts to increase the distance between the bottom thereof and the hook 9.

After the nut 11 has been tightened and the parts brought into the condition shown in Figs. 1 and 2, it will be observed that the spring action in the bar 5, in tending to resume its normal condition, will press the part 6 up against the bottom of the rail base 4, will press the parts 9 and 11 down upon the top of the respective sides of the rail base, and will press the parts 9 and 10 toward each other and clamp the rail base therebetween. It will also be observed that one side of the rail base will be clamped between the straight portion 7 of the bar 5 and the adjustable nut 11.

The spring action in the bar 5 is an important feature of my invention as it compensates for any irregularities between the different parts and maintains all parts of the anticreeper in constant readiness for action at all times and under all conditions.

When the anticreeper is applied to the rail 3 adjacent the cross tie or stationary part 2 of the road bed, and the rail attempts to creep, the anticreeper will engage the part 2 and effectually prevent the creeping of the rail.

In the modification shown in Figs. 4 and 5, the straight portion 7 of the bar 5, instead of having the upwardly-extending end 10, is continued outwardly, providing a screw-threaded end 15 for the bar 5 on which is screwed a nut 16; and interposed between the nut 16 and the adjacent side of the rail base 4, is a rail gripping part 17 having a hole therein through which the bar extends. The rail gripping part 17 is movable on the bar 5 and has a projection 18 extending over and engaging the top of the adjacent side of the rail base; and interposed between the nut 16 and the part 17 is a suitable split nut-lock washer 19, as shown. It will thus be seen that by tightening the nut 16 the rail gripping parts 9 and 17 may be forced toward each other from the position shown in Fig. 5 to the position shown in Fig. 4 to clamp the rail base therebetween. When the parts have been thus tightened, the washer 19 will prevent accidental loosening of the nut 16. The angular relation of the bottom face of the projection 18 to the upper face of the adjacent side of the rail base 4 is such that when the nut is tightened the bar 5 will be sprung from the normal condition, shown in Fig. 5, to the condition shown in Fig. 4; and that the bar will, in tending to resume said normal condition exert an upward pressure against the bottom of the rail and press the rail gripping parts 9 and 17 down upon the top of the rail base 4. Also, when the

nut 16 is tightened the spring in the loop 8 will permit the ends of the bar 5 to be sprung apart and thereafter cause the spring action of the bar to press the parts 9 and 17 toward each other and clamp the rail base 4 therebetween, as the bar 5 tends to resume its normal condition.

I claim:

1. The combination of a railroad rail having a base, and a stationary part of a road bed, of an anticreeper adapted to engage said stationary part and comprising a spring bar extending beneath the rail and having a part engaging the bottom thereof, one end of said bar having a rail gripping part engaging the top of one side of the rail base, a rail gripping part engaging the top of the other side of the rail base and provided with means operative to raise the other end of said bar, said bar being sprung from a normal condition and exerting upward pressure against the bottom of the rail and pressing said rail gripping parts down upon the base of the rail in tending to resume said normal condition.

2. The combination of a railroad rail having a base, and a stationary part of a road bed, of an anticreeper adapted to engage said stationary part and comprising a spring bar extending beneath the rail and having a part engaging the bottom thereof and having an upwardly-extending end adjacent one side of the rail base, the other end of said bar having a rail gripping part engaging the top of the other side of the rail base, and a rail gripping part adjustable vertically on said end and engaging the top of the adjacent side of the rail base, said bar being sprung from a normal condition and exerting upward pressure against the bottom of the rail and pressing said rail gripping parts down upon the base of the rail in tending to resume said normal condition.

3. The combination of a railroad rail having a base, and a stationary part of a road bed, of an anticreeper adapted to engage said stationary part and comprising a spring bar extending beneath the rail and having a part engaging the bottom thereof and having an upwardly-extending screw-threaded end adjacent one side of the rail base, the other end of said bar having a rail gripping part engaging the top of the other side of the rail base, and a rail gripping part screwed on to said end and engaging the top of the adjacent side of the rail base, said bar being sprung from a normal condition and exerting upward pressure against the bottom of the rail and pressing said rail gripping parts down upon the base of the rail in tending to resume said normal condition.

4. The combination of a railroad rail having a base, and a stationary part of a road

- bed, of an anticreeper adapted to engage said stationary part and comprising a spring bar extending beneath the rail and having a part engaging the bottom thereof and having an upwardly-extending end engaging one side of the rail base, the other end of said bar having a rail gripping part engaging the top of the other side of the rail base, and a rail gripping part adjustable vertically on said end and engaging the top of the adjacent side of the rail base, the face of said end engaging said base being upwardly and outwardly inclined with respect to said base, said bar being sprung from a normal condition and exerting upward pressure against the bottom of the rail and pressing said rail gripping parts down upon the base of the rail in tending to resume said normal condition.
- 20 5. The combination of a railroad rail having a base, and a stationary part of a road bed, of an anticreeper adapted to engage said stationary part and comprising a spring bar extending beneath the rail and having a part engaging the bottom thereof, and having an upwardly extending screw-threaded end engaging one side of the rail base, the other end of said bar having a rail gripping part engaging the top of the other side of the rail base, and a rail gripping part screwed on to said end and engaging the top of the adjacent side of the rail base, the face of said end engaging said base being upwardly and outwardly inclined with respect to said base, said bar being sprung from a normal condition and exerting upward pressure against the bottom of the rail and pressing said rail gripping parts down upon the base of the rail in tending to resume said normal condition.
- 30 6. The combination of a railroad rail having a base, and a stationary part of a road bed, of an anticreeper adapted to engage said stationary part and comprising a spring bar extending beneath the rail and having a part engaging the bottom thereof, one end of said bar having a rail gripping part engaging one side of the rail base, and means engaging the other end of the bar and the other side of the rail base and operative to raise the adjacent end of said bar and spring it from a normal condition and cause said bar to press parts of the anticreeper toward each other and against the sides of the rail base and to press parts of the anticreeper down upon the top and up against the bottom of the rail base in tending to resume said normal condition.
- 40 7. The combination of a railroad rail having a base, and a stationary part of a road bed, of an anticreeper adapted to engage said stationary part and comprising a spring bar extending beneath the rail and having a spring loop formed therein, means on one end of said bar for engaging one side of the rail base, and means on the other end of said bar for engaging the other side of the rail base, said bar being sprung from a normal condition and pressing parts of the anticreeper toward each other and against the sides of the rail base and pressing parts of the anticreeper down upon the top and up against the bottom of the rail base in tending to resume said normal condition.
- 50 8. The combination of a railroad rail having a base, and a stationary part of a road bed, of an anticreeper adapted to engage said stationary part and comprising a spring bar extending beneath the rail and having a spring loop formed therein, one end of said bar having a rail gripping part engaging one side of the rail base, and a rail gripping part engaging the other side of the rail base and having an opening therein into which the other end of said bar extends and provided with means to adjust it relatively to said bar and thereby spring said bar from a normal condition and cause said bar to press parts of the anticreeper toward each other and against the sides of the rail base and to press parts of the anticreeper down upon the top and up against the bottom of the rail base in tending to resume said normal condition.
- 60 9. The combination of a railroad rail having a base, and a stationary part of a road bed, of an anticreeper adapted to engage said stationary part and comprising a spring bar extending beneath the rail and having a spring loop formed therein and having an upwardly-extending end engaging one side of the rail base, the other end of said bar having a rail gripping part engaging the top of the other side of the rail base, and a rail gripping part adjustable vertically on said end and engaging the top of the adjacent side of the rail base, the face of said end engaging said base being upwardly and outwardly inclined with respect to said base, said bar being sprung from a normal condition and pressing parts of the anticreeper toward each other and against the sides of the rail base and pressing parts of the anticreeper down upon the top and up against the bottom of the rail base in tending to resume said normal condition.
- 70 10. The combination of a railroad rail having a base, and a stationary part of a road bed, of an anticreeper adapted to engage said stationary part and comprising a spring bar extending beneath the rail and having a spring loop formed therein and having an upwardly-extending screw-threaded end engaging one side of the rail base, the other end of said bar having a rail gripping part engaging the top of the other side of the rail base, and a rail gripping part screwed on to said end and engaging the top of the adjacent side of the rail base, the face of said end engaging said base be-

- 4
- ing upwardly and outwardly inclined with respect to said base, said bar being sprung from a normal condition and pressing parts of the anticreeper toward each other and against the sides of the rail base and pressing parts of the anticreeper down upon the top and up against the bottom of the rail base in tending to resume said normal condition.
- 10 11. The combination of a railroad rail having a base and a stationary part of a road bed, of an anticreeper adapted to engage said stationary part and comprising a bar extending beneath the rail and having a part engaging the bottom thereof and having an upwardly-extending screw-threaded end adjacent one side of the rail base, the other end of said bar having a rail gripping part engaging the top of the other side of the rail base, and a rail gripping part screwed on to said end and engaging the top of the adjacent side of the rail base.
12. The combination of a railroad rail having a base, and a stationary part of a road bed, of an anticreeper adapted to engage said stationary part and comprising a bar extending beneath the rail and having a part engaging the bottom thereof and having an upwardly-extending end engaging one side of the rail base, the other end of
- 5 15 20 25 30
- said bar having a rail gripping part engaging the top of the other side of the rail base, and a rail gripping part adjustable vertically on said end and engaging the top of the adjacent side of the rail base, the face of said end engaging said base being upwardly and outwardly inclined with respect to said base.
18. The combination of a railroad rail having a base, and a stationary part of a road bed, of an anticreeper adapted to engage said stationary part and comprising a bar extending beneath the rail and having a part engaging the bottom thereof and having an upwardly-extending screw-threaded end engaging one side of the rail base, the other end of said bar having a rail gripping part engaging the top of the other side of the rail base, and a rail gripping part screwed on to said end and engaging the top of the adjacent side of the rail base, the face of said end engaging said base being upwardly and outwardly inclined with respect to said base.
